UNITED STATES PATENT OFFICE.

FREDERICK SCHWANHAUSSER, OF JERSEY CITY, NEW JERSEY.

STEREOMOTOGRAPH.

1,108,935.

Specification of Letters Patent.

Patented Sept. 1, 1914.

Application filed February 28, 1913. Serial No. 751,387.

To all whom it may concern:

Be it known that I, FREDERICK SCHWANHAUSSER, a citizen of the United States, and a resident of Jersey City, New Jersey, have 5 invented a new and useful Improvement in Stereomotographs, of which the following is a specification.

My invention relates to stereopticon devices and particularly to that class of machines wherein the plates or things to be projected by the stereopticon are mechanically and automatically presented and removed therefrom.

The invention may be contained in a great 15 variety of constructions. For the purpose of showing that a construction embodying the invention is operative, I shall illustrate one of such constructions and I shall hereinafter fully describe the same.

20 The invention consists, in the main, in providing a movable holder, support or container for plates, sheets or objects, images of which are to be projected and which will move in the vicinity of the lenses of the stereopticon, that is, in the vicinity of the position of exposure.

It also consists in a means for automatically inserting the plates, sheets or other objects in the path of the projecting rays of 30 the stereopticon.

It also consists in means for removing the plates, sheets or other objects from the line of the projective rays.

It also consists in providing an interconnecting mechanism whereby a series of 35 plates, sheets or objects may be successively and intermittently presented and removed from the stereopticon.

It also consists in providing a means 40 whereby a plurality of plates, sheets or objects may be projected in rotation.

Different views of the particular construction selected for illustrative purposes are shown in the figures on the drawings forming 45 a part hereof.

Figure 1, is a view of one side of the construction showing the container therefor in section. Fig. 2, is a plan view of the construction. Fig. 3, is another side view. Fig. 50 4, illustrates some of the details for operating the slide used in connection with the particular construction shown. Fig. 5, is a plate holder partly in section.

1, Fig. 1 is a container or cover for closing 55 the parts embodying the invention. It is

placed on the base 2 which supports the elements containing the invention. The base may be supported by legs 3. It may be supported in any other suitable way. A projecting tube 4, containing projecting lenses is adjustably supported on an adjustable pedestal 5 which is also adjustably supported on a standard 6. The standard 6 is secured to the base 2. A condensing lens 7 is also adjustably supported on the pedestal 60 8 which is in turn secured to the base 2. A Nernst glower 9 or other light giving body is supported in line with the lenses which are used for projecting images of objects when inserted in position of exposure. The 65 glower and its regulating parts are contained in a tube or cylinder 10. The cylinder is supported on a pedestal 11.

A means is provided for conventionally assembling a plurality of objects in order 70 that they may be easily manipulated and brought consecutively in position for presentation to the rays of light of the stereopticon. In the particular construction here selected the holder consists of a circular 75 plate 20 which supports the views of the stereopticon. The plate 20, is composed of two parts, an annular plate 21 and a smaller circular concentric plate 22. The parts are secured together by means of the spokes 23. 80 The annular plate is provided with a groove 24 and a plurality of radial recesses 25. Frames 26 shown in Fig. 5, in perspective are supported in the recesses 25 and in the groove 24. Each frame 26 consists of a solid 85 strip 27 made or bent in the form of a U. To the legs of the U are secured clips or channels 28 in which are inserted the stereopticon plates 29. The legs of the U-shaped strip are of unequal length and one leg 30 is 90 provided with an enlarged portion 31. There is inserted in the portion 31, a pin 32 which forms a pivot pin about which the plate frame may be turned. The pivot pins of the frames 26 are inserted in the channel 95 24 when the frame is placed in position on the annular plate 21. Springs 33 are mounted on the annular plate 21 and are located on opposite sides of each plate frame 26. The springs 33 press upon the ends of the 100 pins 32 and hold them in the channel 24. The plates and their supporting frames may thus be easily inserted in position by merely pressing the pivot pins 32 underneath the 105 upturned lips of the free ends of the springs 110

33. By the pressure of the springs 33 upon the pins 32 the plate frames are held in position in the radial recesses 25 in the plate 21.

The shorter leg of the U-shaped strip or plate supporting base 27 rests upon a circular pad or cushion 40 which is located on the disk or inner plate 22. Also a strip of leather or other elastic or flexible material 41 is supported on an inverted U-shaped piece 42. The leather 41 is stretched across the free ends of the legs of the U. The U-shaped piece 42 is supported on an adjustable pedestal 47 which is supported in a standard 48 located on the base 2. The cushion pad 40 and the elastic strip 41 form cushions for the plates as they are swung back and forth about the pivot pins 32. A spring 49 is also secured to the center of the U-shaped piece 42 and serves the double function of breaking the fall of the plate 29 and also holding the plate 29 in the plate frame and in alignment with the projecting rays of the stereopticon.

The plate frames are located radially upon the support 20. The support 20 is mechanically shifted intermittently so as to bring the frames and their plates successively in the vicinity of the projecting lenses of the stereopticon by means of a motor 60. The motor 60 is connected by a belt 61 to a reducing gear box 62. This may be accomplished by the use of worm gears or by any suitable mechanism well known in the arts. The motor actuates a pinion 63 and gear wheel 64. A vertical rod 65 is supported on the gear wheel 64. The rod 65 is provided with a lip 66. Lugs 67 are located upon the plate 20 and are operated step by step by the lip 66 which engages with the lugs 67 upon the completion of each rotation of the gear wheel 64. The lugs 67 ride over a bellied spring 68 which is adapted to hold the plate 20 in the position to which it is moved by the operation of the lip 66. The spring 68 is supported on a pedestal 69 and a base 70. As the lugs 67 alternate with the plate frames in their positions around the circumference of the plate 20, the plate frames are moved successively into alignment with the position of exposure of the stereopticon.

As each plate comes in line with the position of exposure it is tripped over by a mechanism which is also mechanically operated by the motor 60. The post 65 supported on the gear wheel 64 operates a lever 80 which is pivoted to the standard 81 located on the base 2. This is best shown in Fig. 1. The lever 80 operates a link 82 which is connected to a bell crank 83. The free end of the link 82 is provided with a lip 84. The lip 84 is adapted to engage with appendages 85 located on the frames 27 when the link is operated. The lip 66 located on the post 65 first moves the base

plate 20 into position and then the post 65 engages the lever 80 which operates the link 82 and pulls the lip 84 against one of the appendages 85 which causes a plate frame to turn about its pivot pin 32 and drop upon the elastic cushion 41 and in position of exposure.

A means is provided for operating a shutter mechanism for cutting off the light when the plates are moved. This is accomplished by the gear wheel 64 which is provided with a lug or facial cam 90 which operates upon the arm 91. The arm 91 is supported on the shaft or rod 92 which is rotatable in bearings 93. The rod 92 is also provided with an arm 94. The arm 94 is connected to a link 95. The free end of the link is connected to a gravity actuated shutter mechanism 96 of the type well known in the art. The link 95 pushes the shutter mechanism and causes the shutter to close. When the cam surface or lug 90 located on the under side of the cog wheel 64 passes the arm 91, the pressure on the link 95 is relieved and the shutter mechanism opens and exposes the plate which has been dropped into alignment with the axes of the lenses. When the cog wheel 64 completes its rotation, the lug or cam surface 90 operates upon the arm 91 and closes the shutter mechanism 96. The lip 66 then engages with one of the lugs 67 and the supporting base plate 20 is rotated another step. The stereopticon plate which has been dropped into position of exposure, is swung a short distance upon the movement of the base plate 20 and is slid off from the leather strip 41 which forms a smooth nonresistant substantially antifrictional surface and permits free movement of the plate about the axis of the base plate 20 and also forms a reliable cushion for cushioning the fall of the plate when it is dropped into position of exposure. As the plate is moved from the leather strip 41, it passes over and onto the lug or pin 100. The pin 100 is supported on the free arm of the bell crank lever 83. Upon further rotation of the cog-wheel 64 the post 65 engages the lever 80 and operates the bell crank lever 83 whereupon the lip 84 not only engages with the appendage 85 of the succeeding plate frame but also the lug 100 which receives the plate that was dropped during the preceding operation is raised upward until the plate falls into position and the short leg of the frame drops upon the mat 40 located on the inner disk 22. Upon continued rotation of the gear 84, the shutter mechanism is relieved and the shutters are opened and another plate is exposed. Normally the free arm of the bell crank lever 83 rests upon the standard 48 and its fall is cushioned by the cushion 102. The base plate 20 may be placed over

the post 103 which forms a pivot post about which the base plate 20 may be rotated. A stop 104 having a set screw 105 may be secured to the post 103 for holding the 5 plate 20 in position. The supporting base 20 together with the stereopticon plates may be removed as one piece and may be replaced by merely dropping the base plate onto the stop 104. If desired an adjustable 10 thimble may also be secured to the plate 20, which may be placed over the post 103.

What I claim as new and desire to secure by Letters Patent is as follows:

1. In a stereopticon mechanism the combination of a circular base plate, stereopticon plate frames pivotally supported at the outer edge of the said base plate, means for intermittently moving the said base plate so as to bring the said plate frames successively 20 into the vicinity of the position of exposure of the said plates, means for tipping one of the said plate frames into position of exposure and at the same time restoring another of the said plate frames to normal position.

2. In a stereopticon mechanism the combination of a circular supporting base, plate frames removably and pivotally supported in the said base, plates supported in the said 30 plate frames, a shutter mechanism, means for closing the said shutter mechanism, means for rotatably moving the said base intermittently so as to successively bring the said plates in the vicinity of the position of 35 exposure and means for tipping said frames so as to permit the said plates to drop into position of exposure and at the same time to restore to normal position the plate exposed in the preceding operation of the 40 stereopticon.

3. In a stereopticon mechanism the combination of a circular supporting base, plate frames removably and pivotally supported in the said base, plates supported in the 45 said plate frames, a shutter mechanism, means for closing the said shutter mechanism, means for rotatably moving the said base intermittently so as to successively bring the said plates in the vicinity of the 50 position of exposure and means for tipping said frames so as to permit the said plates to drop into position of exposure and at the same time restore to normal position the plate exposed in the preceding operation of 55 the stereopticon, cushioning devices adapted to receive the said plate frames as their positions are changed.

4. In a stereopticon, the combination of a circular supporting base plate, plate frames supported on the said base, means for rotating the said base plate intermittently so as to successively bring the said plate frames in the vicinity of the position of exposure, and means for tipping said plate frames to permit the frames to drop into position of 60 exposure; means for receiving the said frames when falling to position of exposure, and means for restoring each frame to normal position as the succeeding plate frame is tripped and allowed to drop into position 65 of exposure.

5. In a stereopticon mechanism the combination of a base plate, plate frames supported radially on the said base plate, the said plate frames pivotally secured to the 70 outer edge of the said base plate at a point in the outer edges of the plate frames.

6. In a stereopticon mechanism the combination of a base plate, plate frames supported radially on the said base plate, the 75 said plate frames pivotally removably secured to the outer edge of the said base plate at a point in the outer edges of the plate frames.

7. In a stereopticon mechanism the combination of a base plate having springs located 80 radially, plate frames located between the said springs and having pivot pins located beneath the consecutive springs on the base plate.

8. In a stereopticon mechanism the combination of a removable base plate, means for rotating the said base plate, springs located 85 radially on the said base plate, plate frames located between the said springs and removably secured by the said springs.

9. In a stereopticon mechanism the combination of a removable base plate, means for rotating the said base plate, springs located 90 radially on the said base plate, plate frames located between the said springs, the said plate frames having pivot pins extending under the consecutive springs and between the said springs and the said base plate, means for tipping and restoring the said 95 frames.

In testimony whereof, I have signed my name to this specification in the presence of two subscribing witnesses.

FREDERICK SCHWANHAUSER.
